UNITED STATES PATENT OFFICE.

TRACY V. BUCKWALTER, OF ALTOONA, PENNSYLVANIA.

WAREHOUSE-TRUCK.

1,155,836.

Specification of Letters Patent.

Patented Oct. 5, 1915.

Application filed July 30, 1914. Serial No. 854,062.

To all whom it may concern:

Be it known that I, TRACY V. BUCKWALTER, a citizen of the United States, residing at Altoona, in the county of Blair and State of Pennsylvania, have invented certain Improvements in Warehouse-Trucks, of which the following is a specification.

My invention is a warehouse truck of improved characteristics providing increased strength, greater stability, and an extended load supporting frame guarding the wheels, in combination with means for extending the normal load supporting frame, and efficient bearing mechanism.

15 In the accompanying drawings, Figure 1 is a plan view of my improved truck with the frame or load supporting means fully extended; Fig. 2 is a side elevation of the same; Fig. 3 is a sectional view taken on the 20 line 3—3 of Fig. 1; and Fig. 4 is a perspective view of the detached means for extending the frame.

The truck, as illustrated in the drawings, is provided with an axle 1 supported by 25 wheels comprising the hubs 2 having the sheet metal webs 3 and integrally formed peripheral flanges 4 fixed thereto by the bolts 5, the webs flaring outwardly at their peripheries and the flanges inturned therefrom being laminated to form the treads. 30 These wheels are held on the axle, in revoluble relation thereto, by the nuts 6 screwed thereon and the disks 7 which are screwed into the outer ends of the boxes 8, 35 the inner ends of such boxes being screwed on the sleeve 9 through which and the boxes the axle passes freely. Rollers 8' are revoluble in the boxes 8 on the axle 1, being journaled in rings 8" by which they are held 40 in the desired relation, whereby the boxes, together with the parts supported thereby, are carried. Longitudinal sills 10, preferably formed of shaped metal, are fixed on the boxes 8, taper forwardly to the handles 45 11 which are set therein, and are supported by the shaped metal legs 12 fixed thereto adjacent to the handles; the sills diverging toward the handles.

A foot 13 is fixed to the inner ends of 50 the sills 10, short cross pieces 14 and 15 of shaped metal are fixed to the sills adjacent to their inner and outer ends respectively, and intermediate long cross pieces 16 and 17 of shaped metal are fixed 55 to the sills and project beyond the wheels. A metal shape 18 is fixed to the cross pieces

between the sills and side sills 19 of shaped metal are fixed to the outer ends of the members 16 and 17 and provided with the in-turned end members 20 and 21 fixed to the 60 sills 10. The outer or side sills 19 have their main sections substantially parallel and supported by the brackets 19' and 19".

The wheels lie between the inner ends of the respective pairs of sills 10 and 19, between the parts 16 and 21, and below the tops thereof, whereby the load is provided with support above and beyond the wheels and the wheels, while lying beyond the usual limits marked by the sills 10 so as to provide stability, are guarded from contact with obstructions by the parts 19 and 21.

65 The frame extending means comprises the tapered arms 22, of shaped metal, provided with the open circular or U-shaped bearings 23 at the larger and inner ends thereof from which they diverge, the arms being fixed together by the cross pieces or braces 24 and 25.

In operation, as where a load of comparatively bulky material is to be handled, the 70 bearings 23 are yoked on the sleeve 9 and the arms 22 rest on the foot to provide a readily attached and detached auxiliary frame or load supporting means.

75 When the auxiliary frame is not required, it is withdrawn from its connections with the parts 9 and 13, as in Figs. 1 and 2, and stowed below the main frame by reengaging the bearings 23 with the sleeve 9 and engaging the outer ends of the arms 22 by the resilient latches 26 fixed to the inner faces of the main sill 10, as shown in broken lines in Fig. 3.

80 It will be understood that in moving the truck, the relative freedom of revolution of the axle and wheels reduces the resistance to a minimum and greatly facilitates turning.

85 Having described my invention, I claim:

1. A truck having wheels, in combination with a frame having longitudinal exterior and interior sills between which each wheel is housed, said exterior sills having their ends fixed to said interior sills, and handles on said frame.

90 2. A truck having wheels, in combination with a frame having longitudinal members between said wheels, said members having handles thereon, auxiliary longitudinal members exterior to said wheels, and transverse members whereby said longitudinal members are connected.

3. A truck having wheels, in combination with a frame having main longitudinal members between said wheels, and auxiliary longitudinal members having inturned ends fixed to said longitudinal members first named, said wheels being housed between said main and auxiliary members and beneath the tops thereof.
4. A truck having an axle, wheels thereon, a sleeve on said axle, a frame connected with said sleeve, and an auxiliary frame adapted to engage said sleeve.
5. A truck having an axle, wheels thereon, journal boxes in which said axle revolves, a sleeve on said axle connecting said journal boxes, and handles and legs on said frame, a frame supported by said journal boxes.
6. A truck having an axle, wheels revoluble thereon, means within which said axle is journaled, and a frame carried by said means, said frame having legs for supporting and handles for operating said truck.
7. A truck having an axle, journal boxes within which said axle revolves, a sleeve connecting said boxes, a main frame supported on said boxes, said frame having a foot, and a detachable auxiliary frame supported by said foot and sleeve, said aux-

iliary frame having bearings whereby it is 30 adapted to be engaged with said sleeve beneath said main frame and said main frame having means for holding said auxiliary frame in said last named position.

8. A truck having a pair of wheels, a frame having members between which said wheels are disposed, handles fixed to said frame, legs fixed to said frame, a foot piece fixed to said frame, and a transverse member disposed below said frame, the axis of 40 said wheels lying between said foot piece and legs, in combination with an auxiliary frame detachably connected with said transverse member and supported by said foot piece.

9. A truck having a frame comprising a foot piece, legs and handles, in combination with bearing means connected with said frame and an auxiliary frame having open 50 sockets yoked on said bearing means, said auxiliary frame bearing on said foot piece.

In testimony whereof I have hereunto set my name this 25th day of July, 1914, in the presence of the subscribing witnesses.

TRACY V. BUCKWALTER.
